UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

AUTOMATICALLY THREADING SHUTTLE FOR LOOMS.

Application filed April 19, 1923. Serial No. 633,310.

To all whom it may concern:

Be it known that I, EDWARD S. STIMPSON, a citizen of the United States, residing at Hopedale, in the county of Worcester and 5 State of Massachusetts, have invented an Improvement in Automatically Threading Shuttles for Looms, of which the following description, in connection with the accompanying drawings, is a specification, like 10 characters on the drawings representing like parts.

This invention relates to automatically threading shuttles for looms wherein the weft or filling in the shuttle is replenished 15 from time to time while the loom continues to run.

Automatically threading loom shuttles have heretofore been provided with a threading block made of brass or similar soft and 20 yielding material which required to be machined to provide the necessary structure, and then finished to facilitate movement of the thread over the contacting surfaces during threading and subsequent weaving. The 25 relatively soft and yielding character of such threading blocks and the constant attrition to which they are subjected during weaving soon renders such threading blocks unserviceable and frequent renewals are necessitated. Furthermore, when the shuttle enters the shuttle box, it is subjected to considerable pressure, and especially is this the 30 case when the loom "bangs-off," with the result that the threading blocks heretofore used become bent and the unsupported shuttle wood at such times becomes broken. This same objectionable condition occurs, 35 also, where the threading blocks are formed of sheet material cut and bent to shape, because the flexibility of the material fails to give support to the shuttle wood.

An important feature of the present invention, therefore, consists of a threading block for automatically threading loom 45 shuttles formed of cast iron, capable of resisting the wear of the thread thereon during weaving, and having a surface covering of rust-proof material which offers no objectionable resistance to the movement of the thread thereover, either during the shuttle threading operation or subsequent weaving. When a shuttle having the threading 50 block of the present invention is subjected to the shuttle box pressure at the end of its

flight or when the loom "bangs-off," the unyielding character of the threading block is such that the wood of the shuttle is supported between the points of pressure and does not become broken or splintered.

In the prior patent of applicant, No. 1,483,492, dated February 12, 1924, there was shown, described and broadly claimed an automatically threading shuttle having a thread passage extending longitudinally thereof and provided with a top opening 60 for the ready entrance and exit of the thread, and a thread casting and guiding device which functioned to cast or throw the thread from the control of the said device on the formation of a loop or overthrow and 65 partially unthread the shuttle when the latter was suddenly arrested in the replenishing box. The shuttle of the prior patent has been found efficient and effective in practical 70 operation.

In certain aspects of structure, the present invention is a further development of the shuttle of the earlier patent and relates to features which seek to improve the construction and render it more efficient during 80 threading and unthreading, and while the loom continues to operate in the production of cloth.

When the shuttle is partially unthreaded, that is, when it is not delivered from the shuttle through the side delivery eye and the shuttle is picked from the replenishing box, there is liable to be less tension at times on the thread laid in the shed than when the shuttle is fully threaded, and one feature of the present invention, therefore, consists in a thread guiding recess leading towards the end of the shuttle and having a friction pad and breast wall of greater height than the bridge of the threading block and over 85 which the thread is deflected as the shuttle passes across the loom from the replenishing box, the deflection of the thread over the breast wall and the friction pad serving 90 at such times to give the desired amount of 95 tension to the thread.

In the prior patent the thread casting and guiding scroll is shown as secured in position in the thread passage by the bolt ordinarily used in securing a threading block 100 in position. This construction has been found practical and efficient in operation, but the present invention seeks to further se-

cure the thread casting and guiding scroll in position by providing the latter with a foot portion which extends transversely and has a bearing on a part of the threading block.

The above features of the invention and others to be hereinafter described will best be made clear from the following specification and drawings of one good practical form of the invention.

In the drawings:

Fig. 1 is a perspective view of one end of a shuttle containing the present invention, the shuttle being shown as coming to rest in the replenishing box with the formation of a loop or overthrow in the thread;

Fig. 2 is a side elevation of the shuttle shown by Fig. 1;

Fig. 3 is a cross section on line 3—3 of Fig. 2;

Fig. 4 is a perspective view of the threading block detached from the shuttle;

Fig. 5 is a perspective view of the threading block in another position;

Fig. 6 is a view of the threading block looking at the bottom thereof;

Fig. 7 is an enlarged longitudinal section of the threading end of the shuttle showing the wood of the shuttle cut away to form a recess for the threading block and the thread guiding recess with the friction pad therein;

Fig. 8 is a view similar to that of Fig. 7 but showing the threading block secured in the block chamber and the thread or weft deflected over the breast wall of the guiding recess;

Fig. 9 is a perspective view on enlarged scale showing more particularly the side delivery eye and its association with the side opening in the shuttle.

The shuttle 1 has the bobbin chamber 2 for the weft or filling carrier or bobbin 3 on which the weft or filling thread *a* is wound.

The wood of the shuttle is cut away at 4 to provide a threading block receiving chamber which may be provided with an opening 5 leading through the lower wall of the shuttle, as usual, and the side openings 6 for the block securing bolt.

The front wall of the threading block receiving chamber is intersected by the lower wall of the thread guiding recess 7, Fig. 7, formed in the wood of the shuttle, the intersection of the two walls at 8 forming a breast above the longitudinal axis of the shuttle and over which the thread is deflected, as will later appear. Within the thread guiding recess 7 is a friction pad 9 which may be formed of felt or other suitable material to impart the desired amount of friction to the thread when the shuttle is picked from the replenishing box and is not fully threaded.

The threading block 10 is shown as having the two side walls 11 and 12 rising from

the base portion 13, the space between such walls and the base portion forming the longitudinally extending thread passage. Projecting laterally and forwardly from the side wall 12 of the threading block is the thread director 14 having a thread casting or tapering nose portion 15 which may be substantially similar to the corresponding portion in the prior patent. Extending downwardly from the wall 13 of the threading block is the lug 16* which may be desirable in some cases, and when used is adapted to fit the opening 5 in the wood of the shuttle below the threading block receiving recess 4. As will be apparent from Figs. 4 to 6 inclusive, the longitudinally extending thread passage has an open top for the free entrance and exit of the thread, substantially as more fully described in the prior patent, and extending between the two side walls 11 and 12 is the bridge 16, the construction being such that there are no overhanging or overlapping portions formed in the threading block so that it is susceptible of being cast in a single piece complete without machining or finishing.

It has not been possible, heretofore, to construct threading blocks of cast iron in a single piece, because of overhangs, guards and like features and projections which necessitate a substantially solid casting, and while such metal possesses the desired hardness and unyielding character desired, that very attribute has prohibited its use on account of the boring, cutting and undercutting necessary, and further, the surface of cast iron does not lend itself to use in the weave room on account of the atmospheric conditions and the accumulation of rust thereon.

When the threading block is formed with an unobstructed top opening, such as shown and described in applicant's prior patent, a construction is provided which may be readily formed complete of cast iron in a single casting without the necessity of boring, cutting and undercutting, thus providing a wear resisting threading block of increased life and susceptible of repeated use in different renewal shuttles.

As a further feature of the present invention in this connection, the cast iron threading block when formed of a single casting, as described, is provided with a covering or rust-resisting surface having a substantially finished and smooth thread engaging portion, so that the threading block offers no appreciable resistance to the thread movement either in threading or unthreading on the formation of a loop or overthrow and during the weaving operation, and is capable of use in the weave room under the atmospheric conditions there prevailing. It is preferable, though not always indispensable, that the threading block be formed of a single cast iron casting, as described,

and that the rust-resisting surface be provided, which will present no objectionable resistance to the movement of the thread, either in threading or unthreading during weaving.

One good way of providing such rust-resisting surface to the cast iron threading block, consists in heating the cast iron threading block to a substantially dark red heat, plunging the heated threading block into linseed oil, and then baking it or subjecting it to a heat treatment, and while this method of providing the rust-proof surface to the threading block is simple and effective, the invention is not necessarily limited thereto, because applicant believes himself to be the first in the art to provide a threading block of cast iron having a substantially permanent rust-proof covering for use in automatically threading loom shuttles.

The threading block 10 is provided with a vertical slot or opening 17 which extends downwardly through the bottom wall 13 of the block, and into this opening extends the securing portion 18 of the thread casting and guiding device 19. If desired the thread casting and guiding device 19 may be secured to the threading block by a transverse securing bolt 20, as in the prior patent, but to prevent any possibility of the thread casting and guiding device becoming displaced during the operation of the loom, the lower edge portion 21 of the thread casting and guiding device is turned laterally to form a foot which may fit into a recess 22 formed in the lower wall or portion 13 of the block. The foot 21 is probably best shown by Fig. 6 wherein it will be noted that the foot 21 extends laterally over a considerable portion of the lower face of the wall 13 of the block and provides a bearing between the two which has the effect of preventing any tilting movement of the thread casting and guiding device in the thread passage when the parts are in assembled position in the shuttle.

The thread casting and guiding device 19 has the portion next adjacent the bobbin chamber extending upwardly at 23, gradually turning frontwardly at 24 and extending laterally of the thread passage, as more fully described in the earlier patent.

The thread casting and guiding device 19, with the exception of the foot portion 21, may be substantially the same as described in the former application, and needs no further elucidation herein, it being understood that the portion of the thread casting and guiding device commencing adjacent the bobbin chamber forms a thread casting surface for throwing the thread out of the control of said device on the formation of a loop in the thread when the shuttle is suddenly arrested in the replenishing box.

On the formation of a loop, in the manner described, it is desirable that the side walls of the thread casting block adjacent the loop casting portion of the scroll shall not interfere with the passage of the thread, and as contributing to this end, the present invention contemplates that the edge portions of the side walls 11 and 12 adjacent the bobbin chamber shall be inclined upwardly and frontwardly as at 25 and 26, so that should the loop of thread be thrown against the edge of the side wall, it would still not retard the thread casting action of the thread casting and guiding device.

The shuttle is provided with a side opening 27, as usual, for the delivery of the weft or filling thread, and in accordance with the present invention such side opening is provided with a guide eye 28 having the upwardly extending leg portions 29, Fig. 9. One of the upwardly extending leg portions 29 of the guide eye is seated in a recess 30 formed in the shuttle wood, so that the upper end of the leg 29 offers no obstruction to the free entrance of the thread into the side eye. The opposite leg 29 extends upwardly and is seated in a recess 31 formed in the edge of the thread director 14, the result being that should the thread lead backward from the entrance portion of the guide eye during the time the shuttle is in flight, it will not enter the crack or opening 32, Fig. 9, between the rear edge portion of the thread director 14 and the wood of the shuttle, and such condition will maintain even though the wood of the shuttle may shrink.

When the shuttle is arrested in the replenishing box and a loop or overthrow of the thread occurs, as indicated in Fig. 1, the thread is liable to be thrown out of the side delivery eye. Under such conditions, when the shuttle is picked from the replenishing box the shuttle will be only partially threaded and the thread will lead, as indicated in Fig. 8, from the bobbin and finally pass around and into control of the thread casting and guiding device over the bridge 16 of the threading block and be deflected by the higher breast wall 8 of the guiding recess 7 which will direct the thread into contact with the friction pad 9, so that when the shuttle passes across the loom from the replenishing box, sufficient tension will be placed upon the thread to insure it being properly laid in the shed.

As will be noted from Fig. 8, the bridge 16 over which the thread passes during threading and subsequent weaving is slightly above the tapering end portion of the thread casting and guiding device, thereby insuring a proper control of the thread both during threading and subsequent weaving. During the weaving operation the thread passes through the thread casting and guiding device over the bridge 16 and downwardly under the horn of the

threading block, then outward through the side delivery eye, such course of the thread imparting thereto the necessary tension during weaving.

8. What is claimed is:

1. An automatically threading loom shuttle having a threading block receiving chamber and side delivery eye, a threading block secured in said chamber and having a longitudinally extending thread passage with an open top for the unobstructed entrance and exit of the thread the side walls of the thread passage being inclined upwardly and frontwardly from the bobbin chamber, a thread casting and guiding scroll secured in the thread passage and having an upwardly, frontwardly and laterally extending thread casting edge adjacent the bobbin chamber constructed and arranged to cast the thread from the scroll on the occurrence of a loop as the shuttle is arrested.

10. A thread passage which is open at its top for the unobstructed entrance and exit of the thread, a thread casting and guiding device in the thread passage, a bridge crossing the thread passage frontward of the thread casting and guiding device, a thread guiding recess having a breast wall at a higher elevation than the top of the bridge over which the thread is deflected when the shuttle is partially unthreaded and is picked from the 15 replenishing box, and a tension pad in the guiding recess frontward of the breast wall.

2. An automatically threading loom shuttle having a threading block receiving chamber and a side delivery opening formed in 20 the wood of the shuttle, a threading block secured in the said chamber and provided with a thread passage which has an unobstructed top opening for the free entrance and exit of the thread, a thread casting and 25 guiding device in the open thread passage, and a side eye located in the side opening of the shuttle with an upwardly projecting leg of the eye extending into and covered by the wood of the shuttle at one side of the opening 30 and the other leg extending into the threading block at the opposite side of the opening.

3. An automatically threading loom shuttle having a threading block receiving chamber and a side delivery opening, a threading 40 block secured in said chamber and having a thread passage with an open unobstructed top for the free entrance and exit of the thread, a thread casting scroll having a securing portion extending into the threading block with its lower part turned laterally to 45 form a foot bearing on a part of the threading block, the part of the scroll adjacent the bobbin chamber extending in an upward, frontward, and lateral direction forming 50 a thread casting portion.

4. A threading block for loom shuttles having a longitudinally extending thread passage with an open unobstructed top for the free entrance and exit of the thread, a thread casting and guiding scroll having the part adjacent the bobbin chamber extending in an upward, frontward, and lateral direction to form a thread casting portion, and a securing portion extending downward from 55 the scroll into the threading block and provided with a lateral foot below the thread passage bearing on the threading block to prevent displacement of the scroll during 60 weaving.

65. 5. An automatically threading loom shuttle having a threading block receiving chamber and side opening, a threading block secured in said chamber and having a longitudinally extending thread passage with an open top for the unobstructed entrance and exit of the thread the side walls of the thread passage being inclined upwardly and frontwardly from the bobbin chamber, a thread casting and guiding scroll secured in the thread passage and having an upwardly, frontwardly and laterally extending thread casting edge adjacent the bobbin chamber constructed and arranged to cast the thread from the scroll on the occurrence of a loop as the shuttle is arrested.

6. As an article of manufacture, a threading block for automatically threading loom shuttles formed of cast iron and having the thread engaging portions of the block overlaid by a smooth rust-proof covering which offers no objectionable resistance to the movement of the thread thereover.

7. As an article of manufacture, a threading block for automatically threading loom shuttles formed of cast iron and having the thread-engaging surfaces thereof covered by a rust-proof and substantially non-frictional material adhesively secured thereto to present a smooth thread-engaging surface to the thread.

8. A threading block for loom shuttles having a longitudinally extending thread passage with an unobstructed top opening for the ready exit of the thread on the occurrence of a loop or overthrow as the shuttle is arrested in the shuttle box said threading block being formed complete of cast iron, and a thread casting device in the thread passage for casting the thread upwardly through the open top of the threading block on the occurrence of a loop or overthrow.

9. A threading block for loom shuttles having a longitudinally extending thread passage with an unobstructed top opening for the ready exit of the thread on the occurrence of a loop or overthrow as the shuttle is arrested in the shuttle-box said threading block being formed complete of cast iron and provided with a surface covering presenting no obstruction to the thread movement in the threading or unthreading of the shuttle, and a thread casting device in the thread passage for casting the thread upwardly through the open top of the threading block on the occurrence of a loop or overthrow.

10. The method of forming a threading block for automatically threading loom shuttles which consists in forming the block of cast iron, then applying to the thread-engaging surfaces of the block a rust-proof covering, and then subjecting the block to a heat treatment to secure the covering thereon and cause it to present a rust-proof surface

for the passing of the thread thereover during weaving.

11. A threading block for loom shuttles having a longitudinally extending thread passage and formed complete of cast iron, the cast iron block being provided with a smooth rust-proof surface covering which presents no objectionable obstruction to the thread movement, and a thread guiding device in the thread passage.

12. A threading block for automatically threading loom shuttles having a longitudinally extending thread passage with an open top for the entrance and exit of the thread, a thread casting and guiding device in the thread passage for casting the thread upwardly on the occurrence of a loop or overthrow when the shuttle is arrested and provided with a securing portion extending downwardly and having a deflected foot which bears upon the threading block to pre-

vent displacement of the thread casting and guiding device during weaving.

13. An automatically threading loom shuttle having a threading block receiving chamber and side opening, a threading block secured in said chamber and having a longitudinally extending thread passage with an open top for the unobstructed entrance and exit of the thread, the side walls of the threading block thread passage being inclined upwardly and frontwardly from the bobbin chamber to direct the thread upwardly on the occurrence of a loop or overthrow, and a thread casting and guiding device in the thread passage to cast the thread upwardly from the thread passage on the occurrence of a loop or overthrow as the shuttle is arrested.

In testimony whereof, I have signed my name to this specification.

EDWARD S. STIMPSON.
